UNITED STATES PATENT OFFICE.

CHARLES E. JONES, OF CHICAGO, ILLINOIS, ASSIGNOR TO METAL ARTS & CRAFTS CO., OF CHICAGO, ILLINOIS, A CORPORATION OF ILLINOIS.

DESIGN FOR AN ADJUSTABLE CLAMP-ARM FOR SUPPORTING CANDLES.

47,260.

Specification for Design.

Patented Apr. 27, 1915.

Application filed February 5, 1915. Serial No. 6,388. Term of patent 7 years.

To all whom it may concern:

Be it known that I, CHARLES E. JONES, a citizen of the United States, residing at Chicago, in the county of Cook and State of Illinois, have invented a new, original, and ornamental Design for an Adjustable Clamp-Arm for Supporting Candles, of which the following is a specification, reference being had to the accompanying drawing, forming part thereof.

The figure is a side elevation of an adjust-

able clamp arm for supporting candle on edge of light reflecting bowl, showing my new design.

I claim:

The ornamental design for an adjustable clamp arm for supporting candle, as shown.

CHARLES E. JONES.
